ARCH-SUPPORT.

1,131,900.

Specification of Letters Patent. Patented Mar. 16, 1915.

Application filed February 11, 1914. Serial No. 817,989.

To all whom it may concern:

Be it known that I, ROBERT E. BELCHER, a citizen of the United States, and a resident of Chicago, in the county of Cook and State of Illinois, have invented certain new and useful Improvements in Arch-Supports, of which the following is a specification.

My invention relates to arch supports and contemplates improved features of construction, arrangement and adjustability.

My invention is particularly concerned with arch supports in which metallic spring plates are superposed. In prior devices of this class the superposed spring plates are free to give and flex under the wearer's weight but no provision is made to limit such flexure, the result being that the plates are bent beyond their elastic limit and will eventually flatten so that the arch support becomes ineffective for the purpose for which it was intended. It is also very desirable that the wearer himself may be able to adjust the arch supports, that is, to make adjustment to increase or decrease the height of the arch. For example where a person with a broken arch decides to wear arch supports, such supports should at the beginning be low and comparatively flat so as not to immediately raise the foot arches into normal position. Gradually, however, the height of the arch support should be increased so as to bring the foot arch gradually to normal. In prior structures such adjustment could not be readily effected by the wearer himself but special mechanical devices or machines were necessary. It is, however, very desirable that the wearer himself may be able to effect such adjustment in order that he may obtain the greatest amount of comfort and good from the supports.

One of the important objects of my invention is to provide spring plates which are free to flex under the wearer's weight and movements but whose flexure and relative movement is limited in order that the elastic limit is never reached, the plates being allowed considerable play and flexure without danger of their becoming flattened.

Another important object of the invention is to provide such construction and arrangement that the plates can readily be bent by hand by the wearer himself in order to raise and lower the support arch as desired.

The construction and arrangement by means of which the above and other objects are accomplished are clearly pointed out in the specification and illustrated on the accompanying sheet of drawings in which—

Figure 1 is a side elevational view of an arch support, Fig. 2 is an under side view thereof showing the plates in normal interlocked position, Fig. 3 is a similar view showing the plates separated in order that they may be readily individually bent and adjusted, and Fig. 4 shows a modified arrangement for interlocking the plates.

The arch support comprises the metallic top or arch plate 1, the lower metallic supplemental plate 2, and the leather cover 3 forming an insole. The top or arch plate 1 has one lateral edge 4 curved or curled upwardly to fit the inside curve of the foot instep, as is well understood. The insole 3 is preferably secured to this arch plate as by means of rivets 5 and 6, and the corresponding side 3' of the insole is extended and follows the upward curve 4 of the arch plate as is well understood.

The supplemental plate 2 is riveted at one end to the corresponding end of the arch plate in order that such plate 2 may swing about its pivot with relation to the arch plate. As shown, the rivet 7 pivots the front ends of the plates together and the plate 2 is longer than the arch plate and broadened out at its ends in order to give ample bearing surface for the ends of the arch plate during use of the support. The supplemental plate, like the arch plate is bowed but not to as great a degree as the arch plate so that the arch plate rests only at its ends on the supplemental plate. The plates are stamped from metal which is elastic within certain limits and which can readily be bent by hand, as for example German silver. By virtue of the pivot connection 7 the supplemental plate 2 can be swung into position at substantially right angles with the arch plate (Fig. 3) to thus leave both plates free to be readily individually bent to vary the degree of bow thereof and therefore to adjust for the height of the arch support.

Describing now the means for yieldingly locking the plates together after bending and adjustment thereof, the arch plate has extending downwardly therefrom one or more pins 8, 8', and the supplemental plate 110

has one or more holes or openings 9^a, 9^b and 9^a, 9^b for the pins respectively. Preferably the pins are provided with heads 10, 10' and the supplemental plate has transverse guide slots 11, 11' to the longitudinal holes or slots, and the entrance edges of the slots are well rounded in order that the guide slots will readily receive the pins when the supplemental plate is swung toward normal position after adjustment of the plates. When adjusting the plates the supplemental plate should preferably be unbowed sufficiently in order that when the plate is swung to closed position the inner edges *e* of the guide slots will abut against the respective pins under the heads thereof and in order that the plates will be locked against pivotal displacement by the engagement of the inner ends or pockets *f* of the longitudinal slots with the pins. When the supplemental plate is brought to normal position the pins will snap into the inner ends *f* of the pockets and accidental displacement of the plates will be prevented, although the separation thereof can be readily accomplished by slight pull on the supplemental plate. In order that a better hold may be obtained on the supplemental plate a hole 12 is provided in its end for receiving a button-hook or other suitable implement.

In Fig. 2 the pins are shown in the longitudinal slots 9^b and 9^b, and when the arch support is inserted in the shoe and the weight and movements of the wearer act thereon, both plates will bend and the heel end of the arch plate will play longitudinally on the supplemental plate, and such relative longitudinal movement of the arch support with reference to the supplemental plate is limited by the lengths of the longitudinal holes or slots in which the pins play. For the setting in Fig. 2 the heel end of the arch plate can move relative to the supplemental plate until the outer ends *g* of the slots 9^b and 9^b reach the pins, and thereafter the supplemental plate will act as a tie or chord to prevent further longitudinal movement and flattening of the arch plate. It will be noted that the slots 9^a and 9^a are longer than the slots 9^b and 9^b. This is for the purpose of allowing for greater relative longitudinal movement of the plates if such is desired. If such greater movement is desired, the supplemental plate is swung farther until the longer slots receive the pins. The longest slot is, however, not long enough to allow flattening of the arch plate beyond its elastic limit so that after each depression or flattening of the arch plate, as during walking of the wearer, the plate will return, the pins playing back and forth in the longitudinal slots of the supplemental plate and the supplemental plate preventing further flattening of the arch as soon as the pins reach the outer ends of these slots.

In Fig. 4 pins 8, 8' are not headed and I have omitted entrance ways to the slots in the supplemental plate. With this arrangement after the plates have been swung apart and adjusted the supplemental plate is swung back to normal across the tops of the pins and then under slight pressure against the center of the supplemental plate the end of the plate will be drawn in to bring the slots in register with the pins and the pins will then be at the inner ends of the slots, and when the support is in use the pins will travel back and forth in the slots in the same manner as in the arrangement of Fig. 2.

I thus provide a very efficient arch support in which both the arch plate and the supplemental plate are springy and operate and co-operate to respond to the weight and movements of the wearer. If undue weight or pressure is brought on the arch plate during wearing, the supplemental plate will act as a tie to prevent flattening of the arch plate beyond its elastic limit so that the arch plate will not be pressed out of adjustment and will always be returned to its normal position after the pressure has been released therefrom. The pivotal connection of the supplemental plate with the arch plate allows swinging apart of the plates in order that each may be readily bent and adjusted, but such pivotal connection keeps the plates otherwise locked together, and after adjustment of the plates the pins and slots can be readily brought into interlocking engagement. There is therefore nothing requiring special skill in the adjustment of the support and such adjustment can be accomplished by the wearer himself very readily and perhaps with greater satisfaction than if performed by some one else.

I do not desire to be limited to the exact construction and arrangement shown as modifications could no doubt be made which would still come within the scope of the invention.

I claim as follows:

1. An arch support comprising a bowed arch plate, a supplemental plate below the arch plate and both plates being of spring metal and pivoted together at their toe ends, the supplemental plate being longer than the arch plate to form ample bearing surface for the ends of the arch plate and said supplemental plate being also bowed but to less extent than said arch plate, and a pin extending from one of said plates at the heel end thereof and having a longitudinal slot in the other plate for receiving said pin, said slot and pin interlocking the heel ends of the plates but allowing relative longitudinal movement of the plates.

2. An arch support comprising a bowed arch plate and a bowed supplemental plate below said arch plate, said plates being piv-

- oted at one end to enable such plates to be 5
swung to an angle with each other, both
plates being of spring material and the sup-
plemental plate being bowed to less extent
than the arch plate, and means affording de-
tachable connection with the other ends of
the plates and arranged to allow relative
longitudinal movement of the plates at such
connection during walking.
- 10 3. An arch support comprising a bowed
arch plate and a supplemental plate, both
plates being of spring metal and the sup-
plemental plate being also bowed but to
less degree than the arch plate, the toe ends
15 of said plates being pivoted together to
allow swing of said plates to an angle with
each other in order that the plates may be
individually readily bent to adjust their
curvature, and latch mechanism for de-
20 tachably securing the heel ends of the plates
together and arranged to allow limited rela-
tive longitudinal movement of said plates
at such latch connection during walking.
4. An arch support comprising a bowed
25 arch plate bowed longitudinally and curved
transversely to fit the arch of the foot, a
supplemental plate below the arch plate
longer than the arch plate to extend beyond
the ends of the arch plate and to form a
30 continuation thereof, both plates being of
spring metal and the supplemental plate
being also bowed but to less degree than the
arch plate, the plates being pivoted at one
end to allow swing thereof to an angle with
35 each other in order that each plate may be
readily bent to adjust the longitudinal curva-
ture thereof, and latching means for de-
tachably securing the other ends of the
plates together in parallel position, said
40 latching means being arranged to allow lim-
ited relative longitudinal movement.
5. An arch support comprising an arch
plate arched longitudinally and curved
transversely to fit the instep of the foot,
45 a supplemental plate below the arch plate
longer than the arch plate and also arched
upwardly but to less degree than the arch
plate, both plates being of spring metal
and connected at one end by a pivot pin
50 tending to hold the plates vertically to-
gether, said pivot pin allowing the plates
to be swung away from each other in order
that either plate may be readily bent to
adjust its arch curvature, and a pin extend-
55 ing from the other end of one of the plates,
and the corresponding end of the other plate
having an opening for receiving the pin
to lock the plates together.
6. An arch support comprising an arch
60 plate arched longitudinally and curved
transversely to fit the instep of the foot,
a supplemental plate below the arch plate
also arched upwardly but to less extent than
the arch plate, both plates being of spring
65 metal and connected at one end by a pivot
pin tending to hold the plates vertically
together, said pivot pin allowing the plates
to be swung away from each other in order
that either plate may be readily bent to
70 adjust its arch curvature, and a pin ex-
tending from the other end of one of the
plates, and the corresponding end of the
other plate having an opening for receiv-
ing the pin to lock the plates together, said
75 opening being elongated to allow limited
relative longitudinal movement between the
plates whereby one plate will primarily sup-
port the entire weight.
7. An arch support comprising a bowed
arch plate arranged to fit the instep of the
80 foot, a supplemental plate below the arch
plate also bowed but to less extent than the
arch plate, said plates being both of spring
metal and pivoted at one end in order that
they may be swung away from each other
85 to allow ready bending of either plate to
adjust the arch curvature thereof, and a pin
extending from the other end of one of the
plates, the other plate having a transversely
extending notch or slot for receiving the pin
90 when the plates are brought together into
parallelism, and the inner end of said trans-
verse slot being enlarged longitudinally in
order that there may be limited relative lon-
gitudinal movement between the plates un-
95 der pressure on the support.
8. An arch support comprising an arch
plate arched longitudinally and curved
transversely in accordance with the instep
of the foot, a supplemental plate below the
100 arch plate longer than the arch plate, both
plates being of spring metal and the sup-
plemental plate being arched upwardly but to
less degree than the arch plate, said plates
being pivoted together at their toe ends in
105 order that the plates may be swung apart to
allow ready bending thereof to adjust their
arch curvature, and a pin extending down-
wardly from the heel end of the arch plate
and having a head, the heel end of the sup-
plemental plate having a transversely ex-
110 tending slot for receiving the pin when the
plates are swung to parallel normal pos-
ition, the inner end of said slot being longi-
tudinally enlarged in order to allow limited
115 relative longitudinal movement between the
plates under pressure on the support during
wear.
9. An arch support comprising an arch
plate arched longitudinally to fit the instep
120 of the foot, a supplemental plate below the
arch plate, both plates being of spring metal
and the supplemental plate being arched
upwardly but to less degree than the arch
plate, said plates being pivoted together at
125 their toe ends in order that they may be
swung apart to allow ready bending of
either plate to adjust the curvature thereof,
and a pin extending from the heel end of
one of the plates, the other plate having at
130

its heel end a slot extending transversely from one edge thereof for receiving the pin when the plates are swung into parallel normal position, said slot being of greater width than the pin in order to allow limited relative longitudinal movement between the plates.

10. An arch support comprising an arch plate arched longitudinally to fit the instep 10 of the foot, a supplemental plate below the arch plate, both plates being of spring metal and the supplemental plate being arched upwardly but to less degree than the arch plate, said plates being pivoted together at 15 their toe ends in order that they may be swung apart to allow ready bending of either plate to adjust the curvature thereof, and a pin extending from the heel end of one of the plates, the other plate having at 20 its heel end a slot extending transversely from one edge thereof for receiving the pin when the plates are swung into parallel normal position, said slot having a plurality of enlargements extending longitudinally of 25 the plate for receiving the pin in order to allow limited relative longitudinal movement of the plates.

11. An arch support comprising a bowed arch plate and a supplemental plate below 30 the arch plate also bowed but to less degree than the arch plate, and means locking said plates vertically together but arranged to permit limited relative longitudinal bodily

movement of the plates whereby said arch plate may flatten independently of the supplemental plate to primarily support the entire weight, both plates supporting the weight and flattening after such limited relative movement.

12. An arch support comprising bowed 40 upper and lower arch plates, the lower arch plate being bowed to less degree than the upper plate, and pin and slot connection between the plates arranged to allow limited flattening of the upper arch plate independently of the lower plate whereby said upper arch plate will primarily support the entire weight.

13. An arch support comprising an upper arch plate and a lower arch plate, both 50 plates being bowed but said lower arch plate being bowed to less extent than the upper arch plate but being longer than the upper arch plate to form a seat for the ends thereof, and a longitudinally yieldable connection between the plates for allowing limited flattening of the upper arch plate before the lower arch comes into play.

In witness whereof, I hereunto subscribe my name this 9th day of February, A. D. 60 1914.

ROBERT E. BELCHER.
